UNITED STATES PATENT OFFICE.

AUGUSTUS C. HINCKLEY, OF POCATELLO, IDAHO.

DEVICE FOR CAUSING THE WHEELS OF A LOCOMOTIVE TO SPIN UPON A TRACK.

1,177,519.

Specification of Letters Patent. Patented Mar. 28, 1916.

Application filed October 13, 1915. Serial No. 55,719.

To all whom it may concern:

Be it known that I, AUGUSTUS C. HINCKLEY, a citizen of the United States, residing at Pocatello, in the county of Bannock and State of Idaho, have invented new and useful Improvements in Devices for Causing the Wheels of a Locomotive to Spin upon a Track, of which the following is a specification.

10 This invention relates to a device which may be applied to the frame of a locomotive to cause the wheels of the locomotive to spin upon a track in order that it may be determined whether or not there are any defects 15 in the various working parts of a steam locomotive.

The primary object of the invention is to enable an engine equipped with the invention to be operated upon a short length of 20 track with the operating parts of the engine moving at their maximum speed and with the driving wheels of the locomotive rotating rapidly about their axis yet in such a manner as to cause the locomotive to move 25 slowly along a track.

Another object of the invention is to provide a device of the class described which may be adjustably connected with the frame of a locomotive in such a manner as to insure 30 the device directing a stream of oil upon the tread of the track upon which the locomotive is mounted, in advance of the front and rear drivers of the locomotive, so that upon the flowing of the discharged oil 35 beneath the driving wheels of the locomotive the driving wheels of the engine will revolve at a high rate of speed while the engine is only moving slowly over the rails.

A further object of the invention is to 40 provide a device of the class described with an oil reservoir which may be connected to the main reservoir of an oil burning engine so that a sufficient quantity of oil will be maintained in the oil reservoir of the device while the locomotive is operated under 45 conditions known to railroad men as the breaking in of the locomotive.

A still further object of the invention is to provide the oil reservoir of the device 50 with a member which directs the discharge of oil from the reservoir upon the track, with means for controlling the flow of oil from the reservoir.

With these and other objects in view the 55 invention consists in the novel features of construction, combination and arrangement

of parts, which will be hereinafter described, and particularly pointed out in the appended claims.

The preferred form of the invention has 60 been illustrated in the accompanying drawing, although no restriction is necessarily made to the precise details of construction 65 therein shown, as changes, alterations and modifications within the scope of the appended claims may be resorted to when so desired.

Like characters of reference denote corresponding parts throughout the several views 70 of the drawing.

Figure 1 is a side elevation of a section of track showing a locomotive mounted thereon with the invention applied thereto. Fig. 2 is a transverse section on the line 2—2 of Fig. 1. Fig. 3 is a view showing 75 one of the oil reservoirs and the bracket associated therewith removed from the frame of the locomotive. Fig. 4 is a detail perspective view of one of the oil reservoir 80 supporting brackets.

The numeral 1 designates a section of a railroad track which in carrying out the present invention comprises a short portion 85 of a branch line, and mounted upon the track 1 is a locomotive 2.

Secured to the frame of the locomotive 4 at opposite sides of the locomotive and in advance of the front and rear driving wheels 3 are brackets 5, each of said brackets comprising a strip of material having a longitudinally extending slot near one end thereof, which is indicated by the numeral 6, and near its opposite end with an opening 7. The ends of the strips from which the brackets 5 are formed are bent in opposite 90 directions and at right angles to the body of the strips while secured to the body of the strips in spaced relation to the bent ends which contain the openings 7 are arms 8 provided near their ends distant from the 95 body of the strips with openings 9 registering with the openings 7 in one end of the brackets 5.

Adjustably mounted upon each of the brackets 5 by means of bolts and nuts 11 105 which pass through the slot 6 in the brackets are oil reservoirs 11, each of the reservoirs being provided in its top with a filling opening 12 which may be closed by means of a plug, or if the locomotive is of the oil burning type it may have a supply pipe from the oil reservoir of the locomotive connected 110

therewith as shown in Fig. 1 of the drawing.

Communicating with the interior of each of the oil reservoirs 12 is one end of a flexible pipe 14 the remaining end of which is disposed adjacent the tread of the rails of the track and in advance of one of the driving wheels of the locomotive. Each of the flexible pipes 14 is provided with a valve 15 10 in order that the flow of oil from the reservoir to the pipe 14 may be regulated.

When it is desired to use the device for breaking in a new locomotive or in other words causing the wheels of the locomotive 15 to spin upon a track while the various other parts of the locomotive are operating as though the locomotive were traveling at its maximum speed, the brackets 5 are attached to the frame 4 of the locomotive by means 20 of bolts 16 which pass through the openings 7 in one end of the brackets and through the openings 9 in the arms 8 at the rear of the frame of the locomotive after the same has been positioned between the bent ends of the brackets and arms 8. The oil reservoirs 12 are now connected with the lower end of the brackets 5 and adjusted so that the flexible pipes 14 have their discharge ends positioned directly above the rail or track upon 30 which it is desired to spin the wheels of the locomotives, so that, the oil will flow beneath the wheel tread. If the engine is not of the oil burning type the valve 15 is now opened sufficiently to permit a steady flow of oil 35 through the pipe 14 upon each rail from the oil reservoir. The throttle valve of the engine may now be opened and it will be seen that the oil upon the rails will be directed beneath the driving wheels in such a manner 40 as to cause said wheels to spin while the various other parts of the locomotive are operating as though the locomotive were traveling at its maximum speed.

It will of course be understood that if the 45 locomotive is of the oil burning type a valve in the pipes which communicates with the oil reservoirs 12 from the oil reservoir of the locomotive may be opened to insure the oil reservoirs 12 always being filled to their 50 maximum capacity.

Copies of this patent may be obtained for five cents each, by addressing the "Commissioner of Patents, Washington, D. C."

From the foregoing description taken in connection with the accompanying drawing it will be at once apparent that a device for causing the wheels of the locomotives to spin upon the track rails has been provided, 55 which is simple in construction, inexpensive of manufacture and highly efficient in use.

Having thus described the invention what is claimed as new is:—

1. In a device for testing a locomotive by 60 causing the wheels thereof to spin upon a track, a base, wheels mounted to roll upon the base, and means for discharging lubricating material directly on the base beneath the wheel treads. 65

2. In a device for testing a locomotive by 70 causing the wheels thereof to spin upon a track, means for discharging lubricating material from a source of supply carried by the locomotive directly on the top faces of the rail heads beneath the treads of the locomotive drivers.

3. In a device for testing a locomotive by 75 causing the wheels thereof to spin upon a track, brackets connected with the frame of the locomotive and having supporting arms extending transversely of the tread of the rails, a receptacle for lubricating material adjustable longitudinally of each supporting arm, and means for directing the lubricating 80 material upon the tread of the rails carried by the receptacle.

4. In a device for testing a locomotive by 85 causing the wheels thereof to spin upon a track, strips of material having portions thereof adjacent each end bent in opposite directions, one of said bent portions upon each strip being slotted, L-shaped members connected with the strips between the bent portions and co-acting with the strips to 90 secure the same to the frame of a locomotive, and oil reservoirs movable longitudinally of the slotted ends of the strips.

In testimony whereof I affix my signature in presence of two witnesses.

AUGUSTUS C. HINCKLEY.

Witnesses:

F. E. WILSON,
OSCAR ILLI.
